UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

PROCESS OF MAKING WINDOW-ENVELOPS.

1,264,346.

Specification of Letters Patent. Patented Apr. 30, 1918.

Application filed March 2, 1915. Serial No. 11,574.

To all whom it may concern:

Be it known that I, WILLARD E. SWIFT, a citizen of the United States, residing at Worcester, in the county of Worcester and 5 Commonwealth of Massachusetts, have invented a new and useful Improvement in Processes of Making Window-Envelops, of which the following, together with the accompanying drawings, is a specification.

10 The present invention relates to a method of making window envelops, and has particular reference to the type of window envelops which are characterized by a substantially transparent patch secured within 15 the inside of the envelop and covering an opening formed in the front side of the same.

15 The material commonly used for such patches is commercially known as "glacine" 20 paper; the same possesses a considerable degree of transparency, which lends itself peculiarly to the manufacture of such envelops. The present invention is concerned with the production of an envelop of this 25 type in which the window, or transparent patch, is made to possess a greater degree of transparency than is possessed by the windows of such envelops now in ordinary use; the features of said invention are set forth 30 in the following description and pointed out in the annexed claims, reference being had to the accompanying drawings, in which—

35 Figure 1 represents a view of the rear or inner side of an envelop blank, suitable for the application of my invention thereto.

40 Fig. 2 represents a front view of a completed envelop embodying my invention and made in accordance with the method which forms a part of the same.

45 Similar reference characters refer to similar parts in both figures.

The shape of the envelop to which my invention is applied is immaterial; the envelop shown in the drawings, which is illustrative merely, is made from a blank having a body portion 1, forming the front side of the completed envelop, side or end flaps 2 and 3 which are folded inwardly to form the back side of the envelop, a bottom 50 flap 4, and a closure flap 5. The body portion 1 has a suitably disposed elongated opening 6 therein, which is covered by a patch 7 of transparent or "glacine" paper, said patch being somewhat larger than said 55 opening and overlapping the edges of the

same in all directions, being secured to the gummed or top side of the blank by adhesive material, indicated at 8, which surrounds said opening, so that the blank when folded in the ordinary manner, provides an 60 envelop having a transparent covering for the opening in its front side, which covering or patch is attached upon the inside of the envelop.

65 The "glacine" paper ordinarily used as the material for such patches differs widely in composition and texture from ordinary opaque or semi-opaque paper; the "glacine" paper is close-knit, by reason of the preponderance of cellulose matter in the composition thereof, and moreover, said paper presents a smooth, hard and relatively impenetrable surface, quite unlike the nap-like surface of ordinary paper. The cellulose character of the material gives it its 70 transparent quality; however, I have discovered that the degree of such transparency may be very considerably increased by the treatment of one or both surfaces with a liquid, such as a varnish, or other 75 substantially transparent liquid having resinous or other transparent matter in solution.

I am aware that window envelops have 80 been made heretofore by applying oleaginous substances, in liquid form, to a space upon the front or address side of the envelop to render the same transparent, and I make no claim to this method of manufacture, nor to the article produced thereby. 85 In all such prior processes, the production of a transparent panel depends upon the passage of the liquid through the paper from one surface to the other; the adaptability of most commercial grades of paper, 90 from which envelops are made, to this treatment, by reason of the loosely-knit, coarse-fibered composition of the material and the villous, nap-like character of the surface thereof, is well recognized. The 95 action is essentially one of permeation, and as a consequence the greater portion of the liquid is completely removed and isolated from the drying action of the atmosphere, the evaporation of the liquid is practically 100 never completed, and the window or panel, while possessing a certain limited degree of transparency, invariably is of an oily sticky 105 nature on both sides and is never thoroughly dry.

In carrying out my invention, the transparent "glacine" patch 7 is applied to the opening 6 in the envelop blank in the usual manner; in some cases the reverse surface 5 of the patch, *i. e.*, the surface which is not brought into contact with the adhesive 8 surrounding the opening, may already have received a coating of the transparent liquid above referred to, either before or after being 10 cut into patch form. Or, obviously, the coating of transparent liquid may be applied to this surface of the patch after the latter has been secured over the opening in the blank, by any suitable means, such as a 15 brush, or a die, or a roller coated with the liquid. Preferably, a solution having the property of drying quickly is used; but I do not wish to confine myself to the use of such a solution, since it is manifest that 20 the character of the paper itself, by reason of its impenetrability, is conducive to the rapid drying of the liquid, since said liquid lays on the surface of the paper in a thin film, completely exposed to the evaporative 25 action of the air. Consequently there is no impairment of the adhesive qualities of the other surface of the patch since there is absolutely no permeation of the liquid to said other surface to render the same oily, 30 and thereby unsuitable for contact with the glue 8.

Irrespective of whether or not this treatment of the reverse surface of the patch is afforded, the blank, with the patch applied 35 thereto is now in condition for folding, and in condition for the treatment of that surface of the patch lying on the address or front side of the envelop, either before or after the folding of the blank to form a 40 completed envelop, Fig. 2. This latter step involves the subjection of the successively fed blanks, or envelops, as the case may be, to the action of a suitable coating device or die, corresponding in shape to, but 45 slightly smaller than the opening 6 in the address side of the envelop; said die prints or lays a film of the varnish or other transparent liquid upon the outer surface of the patch, preferably just within the edges of 50 said opening 6, as indicated by the broken line 9, Fig. 2. The advantages accruing

from the treatment of the patch in this manner have already been set forth; the transparency of the patch is materially increased, the liquid dries rapidly, owing to its complete exposure to the air, and there is no permeation of said liquid to the reverse side of the patch, necessitating a drying of this side before the blank is folded, or, if already folded, necessitating a delay in 60 stacking the completed envelops to allow the patches of the same to dry. On the contrary, the envelops are ready for instant use as soon as the short time required for the evaporation of the thin film of liquid 65 on the front sides thereof has elapsed.

I claim,

1. The herein described method of making a two-piece window envelop, comprising the attachment of a transparent patch 70 to the inside of an envelop blank to cover an opening in the body of the blank, the coating of the inside surface of said patch with a transparent liquid before said blank is folded, and the folding of said blank to 75 form a completed envelop.

2. The herein described method of making a two-piece window envelop, comprising the attachment of a transparent patch to the inside of an envelop blank to cover 80 an opening therein, and the printing of a film of transparent substance in liquid form upon the outside surface of said patch, within the edges of said opening on the front side of said blank.

3. The herein described method of making a window envelop having a transparent patch covering the opening in its front side, comprising, coating of the inside surface of said patch with a transparent liquid before the blank is folded, folding said blank 90 to form a completed envelop, and printing a film of transparent substance in liquid form upon the outside surface of the patch, within the edges of the opening in the front 95 side of the envelop.

Dated this 25th day of February, 1915.

WILLARD E. SWIFT.
